United States Patent Office

Des. 180,911
Patented Sept. 3, 1957

180,911

WHEEL CHAIR

John G. Leslie and Lawrence N. Robinson, Erie, Pa.,
assignors to Erie City Manufacturing Company,
Erie, Pa.

Application May 11, 1954, Serial No. 30,412

Term of patent 14 years

(Cl. D15—1)

Fig. 1 is front view of a wheel chair showing our new design;

Fig. 2 is a side view of the wheel chair; and

Fig. 3 is an isometric view of the leg rest according to the invention.

The characteristic features of the design are shown by means of full lines in the drawings.

We claim:

The ornamental design for a wheel chair, as shown and described.
